US00D601976S

(12) **United States Design Patent**
Petrillo et al.

(10) **Patent No.:** US D601,976 S
(45) **Date of Patent:** ** Oct. 13, 2009

(54) **WIRELESS CONTROL DEVICE**

(75) Inventors: **David William Petrillo**, Pennington, NJ (US); **Jason O. Adams**, Emmaus, PA (US); **Samuel F. Chambers**, Conshohocken, PA (US); **Gregory Altonen**, Easton, PA (US); **Elliot G. Jacoby**, Glenside, PA (US)

(73) Assignee: **Lutron Electronics Co., Inc.**, Coopersburg, PA (US)

(**) Term: **14 Years**

(21) Appl. No.: **29/326,190**

(22) Filed: **Oct. 14, 2008**

(51) **LOC (9) Cl.** 14-03

(52) **U.S. Cl.** D13/168

(58) **Field of Classification Search** D13/110, D13/162, 168; D19/72; D10/46, 104, 106; D14/218; 315/291; 361/671.09; 340/825.22, 340/825.24, 825.25, 825.31, 825.36, 825.69, 340/825.72

See application file for complete search history.

(57) **CLAIM**

The ornamental design for a wireless control device, as shown and described.

DESCRIPTION

FIG. 1 is a perspective view of a wireless control device according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a wireless control device according to a second embodiment of our new design.

FIG. 8 is a front view thereof.

FIG. 9 is a left side view thereof.

FIG. 10 is a right side view thereof.

FIG. 11 is a top view thereof; and,

FIG. 12 is a bottom view thereof.

The rear views form no part of the design and are omitted.
